CLOCK

Max E. Schlenker, Peru, Ill., assignor to General
Time Corporation, New York, N. Y., a corpora-
tion of Delaware

Application January 18, 1949, Serial No. 286

Term of patent 14 years

(Cl. D42—7)

To all whom it may concern:

Be it known that I, Max E. Schlenker, a citizen of the United States, residing at Peru, in the county of La Salle and State of Illinois, have invented a new, original, and ornamental Design for a Clock, of which the following is a specification, reference being had to the accompanying drawing, forming a part thereof.

Figure 1 is a perspective view of a clock embodying my new design.

Figure 2 is a side elevational view of said clock.

Figure 3 is a back elevational view of said clock.

I claim:

The ornamental design for a clock, substantially as shown.

MAX E. SCHLENKER.
